UNITED STATES PATENT OFFICE.

JOHN VERNON, OF PHILADELPHIA, PENNSYLVANIA.

VENTILATOR.

Application filed March 15, 1921. Serial No. 452,416.

To all whom it may concern:

Be it known that I, JOHN VERNON, a citizen of the United States, residing at Philadelphia, in the county of Philadelphia and 5 State of Pennsylvania, have invented certain new and useful Improvements in Ventilators, of which the following is a specification.

One object of my invention is to provide a 10 ventilator of simple and durable construction which will have parts automatically cooperative to regulate the amount of ventilation proportionately to the strength of the wind.

15 Another object of my invention is to so construct my improved ventilator that it can be readily used in a window and will provide uniform ventilation at all times.

These objects, and other advantageous 20 ends which will be described hereinafter, I attain in the following manner, reference being had to the accompanying drawings in which—

Figure 1 is a front elevation of a window 25 ventilator made in accordance with my invention.

Figure 2 is a top plan view of Figure 1,

Figure 3 is an enlarged section taken on the line 3—3 of Figure 1,

30 Figure 4 is a fragmentary top plan view of certain of the parts shown in Figure 3 with the hood removed,

Figure 5 is a perspective view of the shutter-supporting portion of the device shown 35 in Figures 3 and 4,

Figure 6 is a fragmentary elevation showing in full lines the position into which it is necessary to move the automatically operative shutter to connect or disconnect the 40 same,

Figure 7 is an enlarged face view of the shutter,

Figure 8 is a section taken on the line 8—8 of Figure 7,

45 Figure 9 is a front elevation showing another way of making one of the parts of my invention, and

Figure 10 is a section taken on the line 10—10 of Figure 9.

50 Referring to the drawings and particularly to Figures 1 to 8 inclusive, 11 represents a member which is illustrated in the

form of a board which can be used in a window. This board, as shown in Figures 1 and 2, has two of my improved ventilating devices 12 illustrated in combination therewith. Since these devices 12 are similarly constructed I will only describe one in detail and it will be understood that one or any number of these devices can be used in 60 combination with a board or similar member. My improved device 12 includes a tube 13 which provides a passageway 14 transversely through the member 11. The tube 13 is preferably made of a separate piece from 65 the member 11 and fits within a hole 15 which is cut or otherwise formed transversely through the member 11. The tube 13 can be secured to the member 11 in any suitable manner and I have illustrated for 70 this purpose screws 16. The edge 17 of the tube 13 extends at a slant or incline forwardly and upwardly so that the tube 13 at its top 18 projects further from the front surface 19 of the member 11 than at its bottom 20 as clearly shown in Figure 3.

The top of the tube 13 supports an extension 21 which, in Figures 1 to 6 inclusive, is illustrated as a separate piece from the tube 13 and is secured to the top 18 of the tube 80 by screws 22; said screws passing through slots 23 in the extension 21. The extension 21 overhangs the outermost portion of the edge 17 of the tube 13 and has a transversely extending groove 24 in its top surface; said extension forward of the groove being made comparatively thin and preferably parallel with the adjacent side of the groove to form a lip 25. A shutter 26, as clearly shown in Figures 7 and 8, includes a very thin plate 27 preferably of light weight metal such as aluminum. This plate has a tongue 28 projecting therefrom and below this tongue the plate is of a shape preferably of the same 90 contour as the cross section of the tube 13 taken in the direction of the slant of the edge 17. In the present instance the cross section of the tube 13 is substantially circular and the lower part of the shutter is therefore substantially circular. The tongue 28 has a slot 29 cut therethrough of a contour similar 95 to that of the lip 25 of the extension 21 so that when the shutter is moved into the position shown in full lines in Figure 6, the shut-

ter can be slipped over the lip 25 and hang and freely swing in the bottom of the groove 24. The inner surface of the plate 27 of the shutter 26 is preferably covered by a coating 5 of soft felt 30 and the position of the groove 24 is such that the shutter will normally hang in a vertical position with the felt 30 spaced from the edge 17 of the tube 13; the space between the felt and the edge 17 being 10 greater adjacent the bottom of the tube and shutter than at the top.

A hood 31 which is preferably made of metal, such as copper, is secured to the surface 19 of the member 11 and serves as a 15 covering for the tube and shutter; said hood at its bottom having an opening 32. The hood 31 flares downwardly and adjacent its bottom on its inner surface has a felt pad 33 secured thereto for abutment under certain conditions with the shutter 26 as shown in dot-and-dash lines in Figure 3. In other words, the shutter 26 can swing until it strikes the pad 33 but it will be noted that it will be impossible for the shutter to become 25 accidentally detached from the extension 21 until the hood 31 is removed from the member 11 since the hood does not permit the swinging of the shutter to the extent that it can be slipped off the lip 25. In other words, 30 as previously stated, the shutter must be moved at a greater angle, such for example as shown in Figure 6, before it can be detached from the extension 21.

The arrangement is such that any gentle breezes occurring outside of the ventilator will cause air to pass upwardly between the shutter and the edge 17 of the tube 13 and will then pass through the passageway 14. However, if the wind becomes stronger 40 and passes upwardly through the opening 32 of the hood, a pressure will be produced on the outside of the shutter and swing the shutter toward the edge 17 and thereby reduce the opening between the shutter and the edge 17 of the tube. As has been found in actual use an exceptionally strong gust of wind will cause the shutter to be swung into contact with the edge 17 and cut off 45 entrance of air through the passageway until the strength of the wind decreases.

Under certain conditions I have found that upon change of the wind where the device is used in the window of a room or in a building of any character that there 55 is a counter action and instead of air entering through the passageway 14 it will pass outwardly therethrough and move the shutter into the dot-and-dash line position as shown in Figure 3.

By providing the felt 30 on the shutter 26 and the felt pad 33 on the inner surface of the hood 31, the device is practically noiseless even though the tube 13 and hood 31 are made of metal. The device can be 60 quickly and cheaply manufactured since in

the embodiment as above specifically described, it is merely necessary to provide a tube with a beveled edge and fit the same in the hole 15 of the board 11 and the shutter 26 can be quickly stamped out of metal and the device when completed is neat in appearance.

In Figures 9 and 10, I have shown a form of the tube having an extension 21^a made integral with the remaining portion of the tube and if desired this tube having the integral part can be stamped out of flat sheet metal bent into form as illustrated. I have indicated the tube in this particular construction by the reference character 13^a. In 30 all other respects the construction and use of the tube is similar to that described in connection with the tube 13.

While I have described my invention as taking a particular form, it will be understood that the various parts of my invention may be changed without departing from the spirit thereof, and hence I do not limit myself to the precise construction set forth, but consider that I am at liberty to 20 make such changes and alterations as fairly come within the scope of the appended claims.

Having thus described my invention, what I claim as new and desire to secure by Letters Patent is:—

1. A ventilator including a hood having an open bottom, a tube having an end extending into the hood and provided with an extension having a groove formed therein, 100 and a shutter provided with a tongue having a slot formed therein for the reception of said extension and to permit the tongue above said slot to work in the groove.

2. A ventilator including a tube having 105 its front edge slanting upwardly and forwardly, a support for said tube, a hood covering said tube and open at the bottom, and a shutter mounted to freely swing in front of said tube, said shutter normally resting in a vertical position but adapted to freely swing beyond the vertical position in either direction.

3. A ventilator including a board having a hole; a tube fitting within the hole and having a front end slanting upwardly and forwardly; a shutter mounted to freely swing toward and from said end of the tube, said shutter normally resting in a vertical position but adapted to move beyond said 120 vertical position in either direction under wind pressure; and an open bottom downwardly flaring hood covering said tube.

4. A ventilator including a member providing a passageway and having its front edge slanting upwardly and forwardly, an extension on said member having a groove formed therein and located beyond said edge, a shutter having a portion working in the groove and normally resting in a ver- 130

tical position, a cushion on one side of said shutter for engagement with said edge, and a hood in spaced relation with respect to said edge, open at the bottom and provided with a cushion for engagement with the shutter.

In testimony whereof I have signed my

name to this specification in the presence of two subscribing witnesses.

JOHN VERNON.
